UNITED STATES PATENT OFFICE.

HARRY T. KINGSBURY AND EDWARD J. KINGSBURY, OF KEENE, NEW HAMPSHIRE.

TOY BOAT.

1,335,900.

Specification of Letters Patent.

Patented Apr. 6, 1920.

Application filed August 2, 1918. Serial No. 247,924.

To all whom it may concern:

Be it known that we, HARRY T. KINGSBURY and EDWARD J. KINGSBURY, citizens of the United States, residing at Keene, in the county of Cheshire, State of New Hampshire, have invented certain new and useful Improvements in Toy Boats, of which the following is a description, reference being had to the accompanying drawing and to the figures of reference marked thereon.

Our invention relates to new and useful improvements in toy boats.

An object of the invention is to provide a toy boat in the form of a destroyer, made of wood covered by a plate carrying the superstructures and so arranged that the same may be readily removed to expose the propelling mechanism, so that it can be replaced or repaired when broken.

Another object of our invention is to provide a swinging propeller shaft, so that the propeller can be moved upwardly beyond or in a plane with the rudder, so that in shipping, the propeller will not readily become broken or injured. At the same time, no adjustment is required in lowering the propeller for use.

A still further object of our invention is to provide a simple, cheap and effective boat of this character having certain details of structure and combination of parts herein-after more fully described.

In the accompanying drawings—

Figure 1 is a side elevation of our improved boat showing the propeller in dotted lines in its raised position for shipment;

Fig. 2 is a top plan view with plate removed showing the driving means for the propeller;

Fig. 3 is a longitudinal vertical sectional view;

Fig. 4 is a transverse vertical sectional view taken on the line 4—4 Fig. 1; and

Fig. 5 is a detail perspective view of the propeller supporting housing.

Referring now to the drawings, 1 represents the hull of the boat, which is preferably made of wood and has its upper face hollowed out, as indicated at 2, said hollowed

out portion extending practically from the bow to the stern, as fully shown in Fig. 3 of the drawings. The hull, as shown, is of a long narrow form to represent a torpedo 55 destroyer, and is provided with an overhanging stern 3. Extending through the hull from the bottom and communicating with the hollowed portion 2, is a bored opening 3' which registers with the enlarged 60 transverse recess 4, as shown in Fig. 2 of the drawings. Arranged within the transverse recess is a plate 5 having its upper edge turned laterally in a horizontal direction and secured to the upper face of the 65 hull by nails or screws 6. The ends of the plate 5 are turned laterally, as indicated at 7, and engage the sides of the recess to firmly hold the plate therein against horizontal movement. The plate 5 is provided 70 with a horizontal opening 8, in which is mounted the shaft 9, the forward end of which beyond the plate is provided with a large gear wheel 10. The rear end of the shaft is provided with a hook 11, over which 75 passes one end of a series of rubber bands 12, which form the propelling means.

The opposite ends of the bands 12 pass over a hook 13 carried by the forward end of the shaft 14. The shaft 14, as shown, 80 extends out beyond the stern of the hull and is rotatably mounted and carries a crank 15, by means of which the same is rotated. The stern of the hull is provided with a plate 16 which has its end turned 85 downwardly and through which passes and is journaled the shaft 14. The extreme lower end of the plate is provided with a horizontally bent ear 17, which has one slanting wall 18 and a straight wall 19, 90 which form a ratchet tooth and engages the crank 14 and prevents the backward movement thereof after winding the rubber bands, but allows the ready movement of the crank in the opposite direction for winding.

The plate 5 is provided with the openings 20 and 21, through which extend the hooked ends of the arms 22 and 23 of the housing 24, arranged in the opening 3' adjacent its 100 lower end. The said housing has a slot 25 in its rear vertical wall, through which ex-

tends the propeller shaft 26. The shaft 26, as shown, is arranged in an elongated recess 27 in the bottom of the hull, which intersects the bored opening 3'. The propeller shaft 26, within the housing has rigidly secured thereon the pinion 28, which is of an elongated form, whereby it will at all times properly engage the gear 10 and mesh therewith so that the pinion will receive power therefrom. The rear end of the propeller shaft passes through the wire loop 29 carried by the bottom of the hull, whereby the propeller shaft may be moved to or from the hull, as hereinafter more fully described. The end of the shaft is provided with the propeller 30 and directly above the same is a bored opening 31, extending upwardly through the hull of the boat. The said opening 31 is of a diameter greater than the width of the propeller blades, so that one of the propeller blades can pass into the opening when the propeller shaft is rocked and the propeller will extend but a short distance below the bottom of the boat and will not become injured, thus allowing the closer packing of the boats in shipment. The usual rudder 32 is provided which is frictionally held so that it will maintain its adjusted position.

The plate 16 forms a ledge under which extend the ears 33 and 34 carried by the plate 35, which closes the hollow portion of the hull and carries the superstructure of the boat. In this event, the superstructure comprises the rear gun 36, conning tower 37, guns 38, three smoke stacks 39, 40 and 41. The plate 16 forward of the smoke stack is raised or bulged upwardly to allow for the large driving gear, and said raised portion is provided with the conning tower 42 and the forward guns 43. The sides of the plate are provided with the port holes 44 and also the ears 45, over which the hooks 46 and 47 are turned for locking the plate on the hull. By the foregoing description, it will be seen that applicants have produced a boat having the appearance of a destroyer, in which the propelling mechanism may be readily exposed and at the same time allowing the propeller and its shaft to move close in against the bottom of the hull for shipping.

The turning of the crank twists the rubber band and by holding the propeller upwardly the blades engages the bottom of the hull and are prevented from rotating until the proper amount of twisting is accomplished. The boat is then placed in the water and when the propeller shaft is released it drops down from engagement with the hull and is rapidly rotated by the bands and the boat set in motion by the propeller.

Having thus described our invention, what

we claim as new and desire to secure by Letters Patent, is:

1. In a toy boat, a hull provided with a transverse opening extending through the hull, a bracket located in said opening, a driving shaft journaled in said bracket and provided with a gear located in said opening, a second bracket detachably depending from said first mentioned bracket into said opening, a propeller shaft journaled in said bracket, and a gear on said shaft meshing with the gear on said driving shaft. 75
2. In a toy boat, a hull having driving means therein, a gear adjacent the forward end of the hull and driven thereby, a propeller shaft swingingly supported, and a pinion carried by the propeller shaft and 80 meshing with the gear.
3. In a toy boat, a hull having driving means therein, a gear driven thereby, the hull of the boat having a vertical opening therethrough intersecting said gear, a propeller shaft swingingly supported in said vertical opening, a pinion carried by the propeller shaft within the opening and meshing with the gear, and a guide for the rear end of the propeller. 85
4. In a toy boat, a hull having a driving means therein, the hull of the boat having a vertical opening therethrough, a gear mounted in the hull within the opening and driven by the driving means, a propeller shaft swingingly supported in said vertical opening, an elongated pinion carried by the propeller shaft within the opening and meshing with the gear, and a guide carried by the end of the boat and through which the propeller shaft passes, whereby the propeller may be moved inwardly within a depression in the bottom of the boat. 90
5. In a toy boat, a hull having a driving means therein, the hull of the boat having a vertical opening therethrough, a gear mounted in said opening and driven by the driving means, a housing secured in the lower end of the opening and having a slot in its rear wall, a propeller shaft mounted in said slot, 11 a pinion carried by the shaft within the housing and meshing with the gear, and a guide carried by the bottom of the boat and having a slot therein through which the propeller shaft passes, whereby the propeller and its shaft may be swung upwardly into a cavity in the bottom of the boat. 115
6. In a toy boat, a hollow hull having a driving means therein, the hull of the boat having a vertical opening therethrough and intersecting an elongated recess in the bottom of the hull, a gear mounted in the hull and extending into the opening, a housing mounted in the lower end of the opening and having a slot in its rear face in alignment with the recess, a propeller shaft ex- 120

tending into the recess and passing through the slot in the housing, an elongated pinion carried by the shaft within the housing and meshing with the gear, a guide carried by 5 the bottom of the boat and having a slot through which passes the propeller shaft, a propeller carried by the shaft beyond the guide, and the bottom of the boat having an opening therein above the propeller to allow 10 the propeller shaft to be rocked in the

housing to bring the propeller within the opening.

In testimony whereof we affix our signatures, in the presence of two witnesses.

HARRY T. KINGSBURY.
